UNITED STATES PATENT OFFICE.

ADOLPH BANGERT, OF UNION HILL, NEW JERSEY.

COMBINATION TOOL.

Application filed November 12, 1921. Serial No. 514,539.

To all whom it may concern:

Be it known that I, ADOLPH BANGERT, a citizen of the United States of America, and a resident of Union Hill, county of 5 Hudson, and State of New Jersey, have invented certain new and useful Improvements in Combination Tools, of which the following is a specification.

The present invention relates to tools and 10 has for its object to provide a construction combining in itself several tool elements, such as hammer, pipe wrench, monkey wrench, pipe cutter, etc., which are frequently used in certain work, such as automobile work or the like.

With this object in view my invention consists in the novel construction, combination and arrangement of parts as will be hereinafter described and defined in the 20 appended claims.

In the accompanying drawing similar reference characters denote corresponding parts, and Figure 1 is a side elevation of my device shown in use as monkey wrench; 25 Fig. 2, a longitudinal section on line 2—2 of Fig. 1; Fig. 3, a sectional side elevation of the tool (with the shank partly broken off) shown in use as pipe wrench; Fig. 4 is a cross-section on line 4—4 of Fig. 3; Fig. 5 is a perspective view of the movable jaw-carrying member; Fig. 6 is a side elevation similar to that of Fig. 3 showing the device in use as pipe cutter; and Fig. 7 is a perspective view of a removable jaw applied to 30 the head of the hammer when the device is used as pipe cutter.

Referring to the drawing, 10 denotes the head of a hammer and 11 the stem thereof formed with an extension serving as handle. 40 The inner face of the end '10' of the head is adapted to serve as the stationary jaw of a wrench and may be serrated as at 10². The stem 11 is toothed longitudinally as at 11¹ and carries a slide 12 which is recessed at 45 one of the sides, as at 12¹ to permit it to be slipped over the stem 11 and to be removably mounted thereon. The recess 12¹ is adapted to be closed by a removable plate 13 fitting therein and having a tongue 13¹ adapted to engage a slot or recess 12² in the bottom of the slide and serving to hold the plate in position. To the upper part of the slide is pivoted a finger 21 which when the plate is inserted into the recess 12¹ after the 55 slide is mounted on the stem can be tilted downwardly to lock the plate in position.

Pivoted in the slide as at 14¹ is a pawl 14 having teeth 14² adapted to cooperate with the teeth 11¹ of the stem 11 and serving to lock the sleeve or slide in the position to 60 which it may have been shifted on the stem. This pawl may be actuated by a plate spring 15 fixed at 15¹ to a cross piece 12⁴ of the slide and bearing on the free end of the pawl 14 as best shown in Figs. 1 and 2. 65 The pawl 14 is formed with a cross-pin 14³, which is adapted to project outwardly through a slot 12⁶ of the slide 12 to serve as a grasp.

The top of the sleeve or slide is extended 70 upwardly and formed with a groove 12³ which is open in front and which serves as a socket. In this socket is pivotally mounted at 16² a jaw 16 the forward or outer face of which is serrated as at 16¹ and which in 75 cooperation with the serrated face 10² of the hammer is adapted to act as wrench. In a second cross piece 12⁵ of the slide works a screw bolt 17 which can be set to project into the socket 12³ and bear against the rear 80 face of the jaw 16 thus acting as abutment for the latter when the wrench is in use. By the setting of the screw bolt 17 the jaw 16 can be adjusted to extend with its outer 85 face either parallel or at a slant to the opposite face of the stationary jaw. In the first case the wrench will act as an ordinary monkey wrench, as shown in Fig. 1, and in the second case as pipe wrench, as shown in Fig. 3. 90

Adapted to be detachably mounted over the jaw 10¹ of the hammer head is a member 19 shaped to conform with, but in width somewhat larger than said jaw. At one side 95 said member is provided with a groove 19¹ to permit said member to be slipped over said jaw. At the lower end of said grooved side perforations 19² are provided which are adapted to register with a perforation 10³ in the hammer head and through which a pin 19³ is adapted to be passed for securing said member on the hammer head. The opposite side of said member is adapted to project beyond the serrated face 10² of the jaw, and is provided transversely with an angular cut to form pipe-engaging jaws 20. The tiltable jaw 16 is provided centrally with a comparatively oblong slot 16³ extending longitudinally of the slide 12 and from the front to the rear end of said jaw. This slot is adapted to serve as a socket for a comparatively thin blade 18 to be used as pipe 100 105 110

cutter. The blade when mounted in the slot 16³ is adapted to project forwardly beyond the serrated face 16' of the jaw to engage a pipe that may be held between the angular jaws 20 of the member 19, while its rear end will project into the recess 12³ to bear against the inner end of the screw bolt 17. By setting the screw the cutter may be fed outwardly as the cutting operation proceeds.

Thus the tool described incorporates in itself a number of tool elements that may be frequently required in certain kinds of work and the use of which is greatly facilitated.

What I claim is:—

1. The herein described combination tool, comprising a stationary jaw formed with a stem, a sleeve slidably and adjustably borne on said stem, a tilttable jaw on said slide having a recess, a blade adapted to be removably borne in said recess, an adjustable common rear abutment for both said tilttable jaw and said blade, and a supplemental V-shaped jaw adapted to fit over said stationary jaw and capable of being fixed thereto to cooperate with said blade as pipe cutter.

2. In a tool of the character described, the combination with the stem, of a slide on said

stem having a recess in its bottom and being open on one side, a plate serving to close the open side of said slide and formed with a tongue adapted to engage said recess, and a tilttable member for locking said plate in closed position.

3. The herein described combination tool, comprising a head piece, one end of which serves as hammer and the other end as stationary wrench jaw and formed with a toothed stem, a member slidably mounted on said stem, a vertically tilttable spring-actuated pawl in said member to cooperate with the teeth of said stem, a vertically tilttable jaw carried by said member and having a recess, a blade removably fitted in said recess, an adjustable rear and common abutment for said tilttable jaw and blade, and a supplemental V-shaped jaw adapted to fit over said stationary jaw and to be fixed thereto to cooperate with said blade as pipe cutter.

Signed at New York, this 10 day of October, 1921.

ADOLPH BANGERT.
